US00D540564S

(12) **United States Design Patent** (10) **Patent No.:** **US D540,564 S**
Tai (45) **Date of Patent:** **** Apr. 17, 2007**

(54) **MUSIC STAND**

(75) Inventor: **Jonathan Tai**, Shanghai (CN)

(73) Assignee: **Shanghai Max Precision Instrument Co., Ltd.**, Shanghai (CN)

(**) Term: **14 Years**

(21) Appl. No.: **29/221,825**

(22) Filed: **Jan. 20, 2005**

(51) **LOC (8) CL .....** **06-03**

(52) **U.S. CL .....** **D6/419**

(58) **Field of Classification Search .....** D6/419,
D6/310-312; 248/441.1, 444.1, 446, 460,
248/463, 464

See application file for complete search history.
